UNITED STATES PATENT OFFICE.

HENRIETTA RODGERS, OF CHICAGO, ILLINOIS.

SANITARY HEAD-PROTECTOR.

1,251,107.

Specification of Letters Patent. Patented Dec. 25, 1917.

Application filed March 17, 1917. Serial No. 155,600.

To all whom it may concern:

Be it known that I, HENRIETTA RODGERS, a citizen of the United States, residing at Chicago, in the county of Cook and State 5 of Illinois, have invented certain new and useful Improvements in Sanitary Head-Protectors, of which the following is a specification.

My invention relates to caps and has for 10 its primary object the provision of a sanitary cap which shall be extremely cheap to manufacture and shall also be adjustable to heads of various sizes.

Other objects and advantages of my invention will appear from the following description taken in conjunction with the accompanying drawings which form a part of this specification.

In the drawings

20 Figure 1 is a plan view of the unfolded cap;

Fig. 2 is a plan view of the lobes showing the band folded at a right angle with respect to the plane of the lobes;

25 Fig. 3 is a perspective view of the folded cap.

Reference numeral 10 indicates a band preferably somewhat broader than the ordinary sweat-band in a man's hat. This 30 band is of arcuate shape when flattened out in order that it may substantially conform to the shape of a person's head when its ends are brought together. At one end a plurality of transverse parallel slits 11 are 35 provided in the band 10 while at the opposite end an undercut tongue 12 is formed, the shank 13 of which substantially fits the slits 11, the tongue 12 being flexible enough to pass through the slits but of greater width 40 than the slits when flattened out so that it will practicably secure the ends of the band together, as seen in Fig. 3. By employing as many slits 11 as necessary the band may be made adjustable to fit large or small 45 heads. Formed integrally with the band 10 are two lobes 14 and 15 which are ovalescent in shape and connect with the band at points substantially a quarter of the length of the band from each end of the band, the band 50 itself lying substantially tangent to one of the long sides of each lobe. The cap may be constructed of linen or other suitable cloth, of paper, or of any other convenient cheap flexible material which will prevent 55 grease and other insanitary matter from

passing through it. The object of my invention is to provide for dealers in hats a sanitary cover for the heads of customers who try on various hats, many of which hats remain in the store to be sold to other persons after 60 having been tried on one customer. From the fact that the sanitary cap is very cheap in construction it follows that the store-keeper can afford to throw away each one after it has been used once, thus not only 65 protecting his own goods from becoming greased, and soiled in other ways, but also preventing the passage of vermin from the head of the customer to a new hat tried on the customer and subsequently returned into 70 stock.

The folding of the cap is illustrated in Figs. 2 and 3. In Fig. 2 the lobes 14 and 15 have been bent at right angles to the band 10, and in Fig. 3 the band, following 75 the first bending, has been itself bent into an annulus with the tongue 12 slipped through one of the slits 11 and flattened out to lock the ends of the band together. The lobes 14 and 15 overlap each other in the 80 folded condition of the cap and may be of the proportion illustrated in Fig. 3, with reference to the length of the band, or they may be formed in somewhat larger relative proportion in order to completely cover the 85 head of the wearer.

While I have illustrated and described the preferred embodiment of my invention it is obvious that one skilled in the art may make modifications thereof without departing 90 from the spirit of the invention. I wish, therefore, not to be restricted to the precise embodiment shown, except in so far as the same is limited in the appended claims.

I claim:

1. In a sanitary cap the combination with a band, of means for securing the ends of said band together, and cover lobes, both formed on the same side of said band and of a size sufficient to substantially close one side 100 of the annulus formed by said band.
2. In a sanitary cap the combination of a band provided with slits at one of its ends, an undercut tongue adapted to engage said slits to hold the band in annular 105 formation, and a pair of lobes secured each to the same side of said band and of a size sufficient to substantially close one side of said annulus.
3. In a sanitary cap the combination with 110

an arcuate band formed with interlocking ends, of a pair of lobes secured to the concave edge of said band and of a size sufficient to cover substantially one side of the 5 annulus formed by said band.

4. In a sanitary cap the combination with an arcuate band formed with interlocking ends, of a pair of lobes protruding from the concave edge of said band and connected to 10 the band at points removed substantially one-quarter the length of the band from the respective ends of said band, said lobes being

of a size to substantially cover one side of the annulus formed from said band.

5. A sanitary cap formed of a single piece 15 of fibrous material and comprising in combination a band having interlocking ends, and a pair of cover lobes each formed on the same side of said band, said lobes being of a size to substantially cover one side of 20 the annulus formed from said band.

In testimony whereof I have affixed my signature.

HENRIETTA RODGERS.
